RAZOR BLADE MAGAZINES

James M. Austin, Westbury, N. Y.

Application March 22, 1951, Serial No. 216,978

3 Claims. (Cl. 206—16)

This invention relates to improvements in razor blade 15 changers and magazines.

In my application Serial No. 159,038, filed April 29, 1950 (now abandoned), I disclose a razor blade changer utilizing a magazine adaptable for receiving used blades when exhausted. The present invention is an improvement thereon, utilizing a blade pusher moving diagonally and a diagonal slot in the magazine accommodating the same.

A mechanism and magazine embodying the invention in a preferred form will now be described with reference to the accompanying drawing and the features forming the invention will then be pointed out in the appended claims.

In the drawing:

Figure 1 is a plan view of a blade changer embodying 30 the invention, with the cover lifted and partly broken away;

Figure 2 is a detail plan view of the razor and magazine holding assembly of the device of Figure 1;

Figure 3 is a section on the line 3—3 of Figure 1;

Figure 4 is a detail section on the line 4—4 of Figure 1;

Figure 5 is a view similar to Figure 4, but showing the parts in a different position;

Figure 6 is a section on the line 6—6 of Figure 1;

Figure 7 is an elevation view of a magazine utilizing 40 the blade changer of the invention;

Figure 8 is an elevation view showing the reverse of the magazine of Figure 7;

Figure 9 is a section on the line 9—9 of Figure 8;

Figure 10 is a flat view of the blank used for forming 45 the magazine; and

Figure 11 is an exploded perspective showing the method of assembly of the magazine.

The blade changer comprises a box having a body 1 and hinged cover 2. The box is provided with a clip arrangement 3 for holding a razor as indicated in phantom outline at 4, with the clip arrangement 5 for holding a spare magazine 6 and with a blade changer assembly designated generally by the numeral 7.

In Figures 1 and 6, the razor 10 is shown in full lines in position for a blade change. As in my application above mentioned, means is provided for holding the razor and a pair of magazines in a definite position so that the blade change may be accomplished by operating the blade ejector without need for positioning the razor and magazines with relation to each other by the hands. The razor is of the hoe type, and has a back member 11 carried by a handle 12 and terminating in an angle 13, forming the upper member or cap for holding the blade 14 in position. A guard 15 supports the lower surface of the blade and has a flange 16 lying flat on the member 11 and pressed thereagainst by a spring 17. Lugs 18 on the guard pass through apertures in the back for positioning the guard with reference to the back, and further lugs pass through apertures in the back and extend beyond the surface of the back for use in opening the razor for blade insertion as later described.

2

The blade changer assembly 7 includes a pair of hooks 22, under which the cap portion 13 of the back 11 is placed, as indicated in Figure 6, the elements 22 having angular extensions 23 for holding the cap in position when so placed. The blade changer assembly also includes a clip 24 adapted to pass through an aperture 25 in the back. This clip has sufficient spring to permit insertion of the razor as indicated in Figure 6, and to hold it in the position of Figure 6 when once inserted.

10 The used and new blade magazines are identical in construction, the magazine shown to the right of the various figures being the new blade magazine and the magazine to the left being the used blade magazine. The magazine 30 has a straight extension 31 at one end and an offset extension 32 at the other. Extension 32 is generally parallel to the magazine wall from which it projects but is offset by substantially the thickness of plate 7 adjacent aperture 33. The new blade magazine is held in position as best shown in Figure 3 by extension 32 passing through an aperture 33 in plate 7, so as to come under the plate for holding the magazine down against it. A spring catch 34 is provided for holding extension 31 at the opposite end of the magazine and the magazine is held in position sidewise by a pair of projections 35. An additional spring element 36 may be provided for cooperating with the catch 34 and urging the magazine firmly into position against a front stop 37. The holding means for the used blade magazine may be the same as the means provided for the new blade magazine. The various elements shown in Figures 1, 2 and 3 for holding the used blade magazine are identified by the same numerals as used with the elements holding the new blade magazine with the addition of a prime suffix and require no further description.

20 The magazine may be conveniently formed by stamping and bending operations out of a single piece of sheet metal, as more fully described below. The side shown in Figure 7 will be referred to, for convenience of reference, as the top, while the side shown in Figure 8 will be referred to as the bottom.

25 The top of the magazine is formed with a full length slot between the edges of the bent over portions 40 of the blank of Figure 10. This slot cooperates with the blade changer pusher as more fully described below. The stack of blades is held against the top walls 40 by a spring 43 so as to position the top blade up against the walls or flanges 40 for ejection by the pusher and insertion into a razor. The ejector or pusher comprises an element 44 pivotally and slidably mounted on a bar 45 held in end brackets 46 on the plate 7, and having an ejector tongue 48 adapted to slide back and forth in the slot of the magazine for ejecting the blades therefrom. The bar 45 carrying the ejector is slanted downwardly with reference to the plane of the plate 7, so that as the ejector moves pushing a blade out of the magazine and into the razor, the ejector follows the path of the slot between the upper wall flanges 40 and urges the blade downwardly as well as outwardly from the magazine. When the blades are exhausted, a new blade magazine is inserted in the used blade position for receiving the used blades as ejected from the razor, and the bottom wall 52 of the magazine is spaced from and overhangs end wall 41 to form a slot for receiving the used blades. Rearwardly of this slot, the back wall 52 is struck down to form a deflector bump or projection 53 for purposes described in detail in my above mentioned application. The blade magazine conforms closely to the profile of the blades and a notch 38 may be provided in an end wall to permit the ejector tongue 48 to be positioned in back of the top blade of the stack for ejecting it.

30 The blade changing operation is the same as described in my above mentioned application. The blade changing

mechanism holds the magazines so as to align the top blade in the stack of the new blade magazine when the blade already in the razor is released by springing the guard upwardly from the cap, as shown in Figure 6, and operating the pusher ejects the top blade from the new blade magazine, pushing it into the razor, and pushing the blade within the razor into the used blade magazine. The used blade is cleared out of the way by the bump 53 and spring 43 as described in detail in my above mentioned application.

The mounting of the pusher 48 for diagonal movement and the provision of a diagonal slot in the magazine to permit this is found to produce a marked improvement in the ease of operation of the blade changer. By reason of the diagonal movement of the ejector, it not only pushes the blade out of the inside slot of the magazine but also pushes the back of the blade against the magazine wall and against the cap of the razor, thus positively aligning the blade in its movement.

The magazine can be conveniently formed from a single blank struck and bent out of sheet metal, a suitable blank being shown in Figure 10. The assembly of the blades and spring 43 with the magazine is extremely simple and is indicated in Figure 11, the stack of blades and spring being held by a suitable device and slid into the magazine before bending down one end wall thereof.

What is claimed is:

1. A razor blade magazine comprising a casing, a stack

of single edged blades therein and a spring urging the stack against a wall of the casing; the casing having an exit slot aligned with the top blade of the stack to permit ejection thereof and a pusher slot for accommodating a blade ejector, the pusher slot extending diagonally across the top blade of the stack from a point adjacent a back corner of the blade near the exit slot to a point adjacent an edge corner of the blade near the opposite end of the casing.

10 2. A razor blade magazine according to claim 1 in which the pusher slot runs full length of the casing.

3. A razor blade magazine according to claim 2 in which the spacing between end walls of the casing substantially equals the blade length.
